UNITED STATES PATENT OFFICE.

WILLIAM H. CLARKE, OF OLEAN, ASSIGNOR OF ONE-HALF TO THOMAS W. LARSEN, OF BOLIVAR, AND MRS. M. A. TACK, OF NEW YORK, N. Y.

JAR OR OTHER COVERED VESSEL.

SPECIFICATION forming part of Letters Patent No. 314,109, dated March 17, 1885.

Application filed December 2, 1884. (No model.)

To all whom it may concern:

Be it known that I, WILLIAM H. CLARKE, a citizen of the United States, residing at 5 Olean, Cattaraugus county, New York, have invented new and useful Improvements in Jars and other Covered Vessels, of which the following is a specification.

This invention has for its objects to provide novel and efficient means for clamping a cover 10 on a jar or other vessel; to provide a lever to clamp a cover on a jar, with two separated cam-bearings for acting on the cover; to provide a cam-lever of such construction that when swung to clamp the cover in place the 15 lever will embrace the bail or yoke to which it is pivoted and thereby prevent the bail or yoke from being forced sidewise; to provide means whereby a cam-lever disconnected from the cover to be clamped is prevented from 20 moving sidewise on the cover when swung to clamp the latter on a jar or other vessel, and to provide novel means for pivotally connecting a cam-lever with a swinging bail to clamp a cover in position on a vessel. These objects 25 I accomplish in the manner hereinafter described and claimed, reference being made to the accompanying drawings illustrating my invention, in which—

Figure 1 is a perspective view of the invention applied to a fruit-jar, showing the cam-lever in its clamping position; Fig. 2, a similar view showing the lever elevated to release the jar-cover, the jar being broken away; Fig. 3, detached views of the bail or yoke, cam-lever, and pivot-pin therefor; and Fig. 4, a vertical central sectional view of the top portion of the jar on a reduced scale.

In order to enable those skilled in the art to make and use my invention, I will now 40 describe the same in detail, referring to the drawings, where the number 1 indicates a jar such as is used for fruit; 2, its cover resting on a rubber gasket; 3, a wire band encircling the neck of the jar, and 4 a yoke or bail pivotally connected or jointed at its two ends to the neck-band.

The yoke or bail is bent midway of its ends into an eye, 5, which thus becomes integral with the bail, and provides a simple and economical provision for engaging the pivot-pin 50 6 of the cam-lever 7. The lever is hollow to

constitute two cheek-pieces, 8, substantially its entire length, and the cheek-pieces directly opposite the pivot-pin are formed into two cam-bearings, 9, which afford two distinct and 55 separated surfaces to act on the cover and clamp it on the jar. The cheek-pieces and cam-bearings embrace the bail, and the pivot-pin passes through the cheek-pieces and the eye in the bail, whereby these parts are pivotally united.

The cover is disconnected from the cam-lever and bail, and is centrally provided on its upper surface with one or more lugs or ribs, 10, which are embraced by the cam-bearings 65 10, when the lever is swung to clamp the cover in place, whereby the lever is effectually prevented from sidewise movement when clamping the cover upon the jar.

The lever being hollow its entire length, or 70 approximately so, will embrace and inclose the bail when swung down to secure the cover, and therefore the bail is more effectually prevented from swinging or moving sidewise when the parts are in the locking position; 75 and, further, the lever being pivoted to the bail by a transverse pivot-pin, is caused to swing in the longitudinal plane of the bail, so that sidewise pressure on the bail in no way tends to unclamp the lever, as is the case where 80 a cam-lever swings at right angles to the bail, as heretofore.

By the construction shown and described a broad bearing on the cover is provided, and the cover is therefore pressed evenly upon the 85 jar to secure a perfect and tight joint, and the cheek-pieces provide a greater bearing-surface with less metal than a solid cam of the same size.

The invention is applicable to various constructions of jars, as well as to tubs and other vessels.

Having thus fully described my invention, what I claim is—

1. The combination of the swinging bail, 95 the cam-lever embracing the bail, and provided with two separated cam-bearings, and pivoted to the bail to swing in the longitudinal plane thereof, the cover disconnected from the bail and lever, and the jar or vessel, substantially as described.

2. The combination of the swinging bail,

the cam-lever pivoted to the bail to swing in the longitudinal plane thereof, and having cheek-pieces to embrace the bail, and provided with two separated cam-bearings, the cover, and the jar or vessel, substantially as described.

3. The combination, with the jar, of the swinging yoke having its ends pivotally connected with the neck of the jar and bent intermediate its ends into an eye, the lever embracing the bail, and provided with two cam-bearings, and pivotally connected with the yoke-eye to swing in the longitudinal plane thereof, and the cover disconnected from the bail and lever, substantially as described.

4. The combination of the jar, the swinging bail, the lever having two separated cam-bearings, and pivoted to the bail to swing in the longitudinal plane thereof, and the cover having the central lug or rib which is embraced by the cam-bearings of the lever, substantially as described.

In testimony whereof I affix my signature in presence of two witnesses.

W. H. CLARKE.
